UNITED STATES PATENT OFFICE.

JAMES B. LUDLUM, OF MARION, INDIANA, ASSIGNOR TO JOHN S. LUDLUM, OF MARION, INDIANA.

TELEPHONE-BRACKET.

1,174,881.

Specification of Letters Patent.

Patented Mar. 7, 1916.

Application filed December 30, 1914. Serial No. 879,739.

To all whom it may concern:

Be it known that I, JAMES B. LUDLUM, a citizen of the United States, residing at Marion, in the county of Grant and State of Indiana, have invented a new and useful Telephone-Bracket, of which the following is a specification.

The present invention appertains to brackets, and aims to provide an improved bracket 10 adapted particularly for holding or supporting a desk telephone set, whereby the same may be supported at different vertical positions, and whereby the telephone set may be raised out of the way when not in 15 use.

It is the object of this invention, to provide an adjustable bracket embodying a unique assemblage of component parts, whereby the bracket will permit the telephone set to be swung about a vertical axis, as well as enabling the telephone set to be raised and lowered, and whereby the bracket will be simple, non-encumbering, rigid and inexpensive in construction, inexpensive to 25 manufacture, composed chiefly of bars or strips of metal, and convenient, practical and efficient in its use.

Another object of the invention, is to provide a bracket embodying means for attaching it to a wall or upright support, or upon the top of a desk or other horizontal supporting member.

It is also within the scope of the invention, to provide a telephone bracket which 35 will be improved generally in its construction and details, to enhance the utility thereof.

With the foregoing and other objects in view which will appear as the description 40 proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in its preferred embodiment in the accompanying 50 drawing, wherein:—

Figure 1 is a side elevation of the bracket illustrating the arm thereof raised. Fig. 2 is a slightly reduced side elevation of the bracket with the arm lowered. Fig. 3 is a

top view of the bracket in a position illustrated in Fig. 2. Figs. 4 and 5 are enlarged sectional views taken on the lines 4—4 and 5—5, respectively, of Fig. 1.

In carrying out the invention, the bracket comprises in its main essentials, a supporting base member 1 attachable to the wall, desk or other support, a horizontally swinging member 2 carried by the member 1, a vertically swinging arm 3 carried by the member 2, and a clamp or holder 4 carried by the free end of the arm 3 for receiving and holding the standard of a telephone set or transmitter. The said parts will be taken up and described in detail in the order mentioned.

The supporting or base member 1 embodies an upright or vertical bar or strip 5 having its ends bent angularly as at 6, to project forwardly. The bar 5 is apertured or otherwise provided with means for securing it to a wall or other upright support W as seen in Fig. 2. An upright bolt or spindle 7 is engaged through the angular ends 6 of the bar 5, and carries a lower nut 8.

A supplemental or auxiliary supporting or base member is employed in connection with the bar 5, for applying the bracket to the top of a desk or other horizontal supporting structure D, and to this end, an angular or L-shaped bar 9 has its vertical or upright arm attached to the back of the arm 5, by means of bolts or other securing elements 10, and an inclined brace 11, formed from a bar, is secured between the arms of the bar 9 below the bar 5. The lower end of the brace 11 is bent angularly, as at 12, to rest upon the end portion of the lower or horizontal arm of the bar 9, whereby a bolt or securing element 13 may be engaged through the lower end portions of the bars 9 and 11, while the upper end portion of the bar or brace 11 is bent, as at 14, to bear against the lower angular end 6 of the bar 5, and to be engaged by the bolt 7, so that the nut 8 being tightened, will clamp the lower end 100 of the bar 5 and the upper end of the bar 11 together.

Thus, the bar 11 will brace the structure, so that when the lower horizontal arm of the bar 9 is secured upon the desk or other support, the upright arm or standard 105 of the bar 9 will be held rigid.

The swinging member 2 comprises upper and lower doubled horizontal bars or straps

15, the bends of which are disposed rearwardly and form loops or hinge butts 16 embracing the hinge bolt 7 and bearing against the angular ends 6 of the bar 5, to 5 hinge the member 2 to the member 1. A spacing tube or sleeve 17 is preferably disposed upon the bolt 7 between the loops 16, for holding the bars or straps 15 separated and seated against the angular ends 6 of the 10 bar 5. An upright bar or strip 18 is terminally secured between the ends of the bars 15, by means of bolts 19, and an upright bar 20 is secured between the limbs of the bars 15 by means of rivets or other securing elements 21, the bar 20 being disposed between the bar 18 and bolt 7, and the upper end of the bar 20 projecting above 15 the upper bar or strip 15. Washers 21^a are disposed upon the rivets 21 between the bar 20 and the limbs of the bars 15 to serve as 20 spacers.

The vertically swinging or oscillatory arm 3 comprises upper and lower pairs of bars 22, and upright links 23 terminally pivoted 25 between the bars 22 of the upper and lower pairs, by means of rivets or other pivot elements 23^a. Spacing washers 24 are disposed upon the rivets 23^a between the links 23 and bars 22, the links 23 being preferably formed 30 of bars or strips. That link 23 nearest the member 2, projects upwardly above the upper bars 22, as at 25. The rear or inner ends of the upper and lower bars 22 are pivotally engaged to the upper and lower 35 bolts 19, respectively, between the ends of the bars 15 and the bar 18, the bar 18 serving as a spacer to separate the rear ends of the bars 22, as well as rendering the free portion of the member 2 rigid.

40 The arm 3 is spring pressed to normally assume an upwardly projecting or inclined position, as seen in Fig. 1, and to this end, a coiled wire extractile spring 26 is disposed between the upper end of the bar 20 of the member 2, and the protruding end portion 25 of the respective link 23 of the arm 3, the ends of the spring 26 having the hooks 27 and 28 engaged respectively through an aperture 29 provided in the portion 25, and 50 a notch 30 provided in the upper end portion of the bar 20. The spring 26 being disposed between the upper portions of the member 2 and arm 3, will be out of the way, and will also effectively serve its office of 55 raising the arm 3 and allowing the same to yield or swing downwardly.

As a means for limiting the downward movement of the arm 3, when it is swung to a lowered or horizontal position, as seen in 60 Fig. 2, the lower ends of the upper bars 22 of the arm 3 are extended beyond the upper pivot bolt 19, as at 31, and have recessed or cutaway portions 32 which are engageable with a rivet or stop 33 engaged through the 65 limbs of the upper bar 15 between the up-

per bolt 19 and the bar 20. This will prevent the excessive downward movement of the arm 3, when the arm is lowered.

The holder or carrier 4 comprises upper and lower pairs of horizontal bars 34 70 which have their rear ends pivotally engaged upon rivets or pivot elements 35 engaged through the free ends of the bars 22, the bars 34 being disposed between the free ends of the respective bars 22, and an upright spacer bar or link 36 is terminally engaged to the rivets 35 between the bars 34. An upright bar 37 is secured between the bars 34 of the two pairs between the ends thereof, by means of clamping bolts 38, and 80 the free portions of the bars 34, beyond the bar 37 are curved or bent to provide complementing jaws 29 for receiving and clamping the standard 40 of the telephone set or transmitter. The upper end of the bar 37 is 85 projected or extended above the upper bars 34, as at 41, to engage under the upper or head portion of the standard 40, to support the said standard with the receiver hook spaced above the upper jaws 39, whereby 90 the telephone set will not shift downwardly through the jaws 39 to such an extent, as to raise the receiver hook due to the downward movement of the transmitter standard.

In use, to apply the bracket to a desk, the 95 bars 9 and 11 are applied to the bar 5, whereby the lower arm of the bar 9 may be secured upon the desk or other horizontal support D, as indicated in Fig. 1, whereas if the bracket is to be attached to a wall 100 W as seen in Fig. 2, the bars 9 and 11 are removed, and the bar 5 is secured to the wall. The member 2 being swingable horizontally and carrying the arm 3, will enable the arm 3 to be swung to one side or 105 the other around the vertical axis of the hinge bolt 7, so that the telephone set may be swung conveniently to and from the talking position. The arm 3 being normally raised under the influence of the 110 spring 26, will raise the telephone set out of the way, and the telephone set may be readily lowered and moved forwardly to talking position, since the arm 3 is adapted to swing in a vertical plane. The links 23 115 hold the upper and lower bars 22 substantially parallel at their various positions. By removing the bolts 38, the transmitter standard 40 may be readily placed between the jaws 39, and by then applying and 120 tightening the bolts 38, the said standard will be clamped in place, and the member 4 will be held in all positions of the arm 3, in such a position as to hold the telephone set upright.

125 The salient features of the present invention resides in the fact that the entire bracket is constructed chiefly of bars or strips of metal, rendering the structure simple in construction and manufacture, and 130

rendering it comparatively light and compact, the assemblage of the parts being such that the bracket is thoroughly substantial and efficient in use. It is thought that the 5 other advantages will be obvious from the foregoing, taken in connection with the drawing, without further comment being necessary.

Having thus described the invention, what 10 is claimed as new is:—

1. A bracket comprising a base, a horizontally swinging member carried by the base and comprising upper and lower bars hinged to the base and an upright bar secured to the 15 aforesaid bars and projecting thereabove, a vertically swinging arm carried by the said member and comprising upper and lower bars pivoted to the free ends of the upper and lower bars of the said member, an up- 20 right link pivoted to the bars of the said arm and projecting thereabove, a contractile spring connecting the upper ends of the said link and the upright bar of the said member, and a carrier pivoted to the free ends 25 of the bars of the arm.

2. A bracket comprising a base, an upright hinge bolt carried thereby, a swinging member embodying upper and lower doubled bars having their bends embracing the said 30 bolts, an upright bar secured between the limbs of the said bars and projecting above the same, a vertically swinging arm carried by the said member and comprising upper and lower bars pivoted between the ends of 35 the said doubled bars, an upright link pivoted to the bars of the said arm and projecting thereabove, a carrier pivoted to the free ends of the bars of the arm, and a retractile 40 spring connecting the upper ends of the said link and upright bar.

3. A bracket comprising a supporting member, a vertically swinging arm carried thereby and comprising upper and lower pairs of bars pivoted to the supporting member, upright links pivoted between the bars 45 of the upper and lower pairs, and a carrier pivoted to the free ends of the said bars.

4. A bracket comprising a supporting member, a vertically swinging arm carried 50 thereby comprising upper and lower bars pivoted thereto, and a carrier carried by the free end of the said arm and embodying upper and lower pairs of horizontal bars pivoted to the free ends of the upper and

lower bars of the said arm, respectively, the 55 free portions of the second mentioned bars comprising complementing jaws, and clamping elements engaged through the second mentioned bars.

5. A bracket comprising a supporting 60 member, a vertically swinging arm carried thereby comprising upper and lower bars pivoted thereto, and a carrier carried by the free end of the said arm and embodying upper and lower pairs of horizontal bars 65 pivoted to the free ends of the upper and lower bars of the said arm, respectively, an upright bar disposed between the second mentioned bars, clamping elements engaged through the second mentioned and upright 70 bars, the free portions of the second mentioned bars, constituting complementing jaws.

6. A bracket comprising a supporting member, a vertically swinging arm carried 75 thereby comprising upper and lower bars pivoted thereto, and a carrier carried by the free end of the said arm and embodying upper and lower pairs of horizontal bars pivoted to the free ends of the upper and 80 lower bars of the said arm, respectively, an upright bar disposed between the second mentioned bars, clamping elements engaged through the second mentioned and upright 85 bars, the free portions of the second mentioned bars, constituting complementing jaws, the upper end of the said upright bar projecting above the upper second mentioned bars for supporting an object held between the jaws. 90

7. A bracket comprising an upright bar having angular ends, a hinge bolt engaged through the said ends of the bar, a swinging member carried by said hinge bolt, an L-shaped supporting bar having its upright 95 arm attached to the first mentioned bar, and a brace between the arms of the L-shaped bar, the lower end of the brace being secured to the lower arm of the L-shaped bar and the upper arm of the brace being engaged to 100 the lower end of the said bolt.

In testimony that I claim the foregoing as my own, I have hereto affixed my signature in the presence of two witnesses.

JAMES B. LUDLUM.
